UNITED STATES PATENT OFFICE.

MATHEW A. GOODSPEED, OF FREMONT, NEBRASKA.

DUST-CONSUMER.

981,409.

Specification of Letters Patent. Patented Jan. 10, 1911.

Application filed April 13, 1910. Serial No. 555,212.

To all whom it may concern:

Be it known that I, MATHEW A. GOOD-
SPEED, a citizen of the United States, residing
at Fremont, in the county of Dodge and
5 State of Nebraska, have invented certain
new and useful Improvements in Dust-Consumers,
of which the following is a specification.

My invention relates to new and useful
10 improvements in granite or stone dust consumers.

The objects of my invention are to provide
a practical, economical and efficient dust
consumer, for use in connection with granite
15 or stone pneumatic surfacing machines, and
which will obviate the inconvenience and injurious
effects on the operator attending the use of these
surfacing machines, caused by the dust
20 filling the air, blinding the eyes, filling the
nose and covering the clothes, and settling
on everything in the room where used. And
further objects are to provide a dust consumer
25 that is easily applied to any of the ordinary
granite or stone pneumatic surfacers, without
altering the same, and using the exhaust from
the surfacer mechanism in the operation of the device. I accomplish
these objects by the device illustrated in the
30 accompanying drawings, in which,

Figure 1 is a side view showing the device in connection with the head of an ordinary pneumatic granite or stone surfacing machine. Fig. 2 is a sectional view of the device, with a dotted line showing the surfacing point positioned ready for use. Fig. 3 is a view in detail of the reducing tubes and their relation to each other, as they appear on the interior of the device.

Similar letters refer to similar parts
40 throughout the several views.

Referring specifically to the drawings, 1 is a circular funnel shaped hollow hood, with the upper or small end 2, provided with a tubular neck 3, in which is telescopically 45 adjusted an extension pipe 4, adapted to close up around the lower portion or steel point of the surfacer, as hereafter described. This hood 1 is provided in its side wall with an aperture 5, opening into a dust consuming hollow chamber, 6, which extends horizontally and substantially at right angles thereto. This dust consuming chamber is 50 closed at all points except the aperture at 5 and the bottom, where it is provided with

an opening 7, extending its entire length, and through which the refuse drops after transformation from dust into a congealed or solid form.

8 is a tube vertically penetrating the upper wall of hood 1, and extends downwardly 60 into the interior thereof. The upper end of this tube is adapted to a hose, 9, connecting it with the water supply tank, at 10, which is conveniently located on and attached to the lever of the surfacer. The supply of 65 water from tank 10 is regulated by an ordinary valve, at 11, inserted in hose 9.

12 is a tube extending horizontally through the side wall of hood 1, and forms a right angle or elbow 13, on the interior of the 70 hood, with an arm 14 reaching to a point near tube 8, as it extends downwardly into the interior of the hood 1, the tube 8 and the arm 14 falling centrally in the opening 5 leading to the dust consuming chamber 6, 75 and positioned in such manner as to cause the water passing through tube 8 to fall directly on a plane with the end of arm 14, where it is transformed into spray in the operation of the mechanism, as hereinafter 80 described.

15 is an aperture in the hood 1, conveniently covered with screen to prevent stone chips from escaping, and is provided for the purpose of observation on the part of the 85 operator in the conduct of his work.

Hangers, as at 16—16, are conveniently attached to the hood 1, and the dust consuming chamber 8, and adapted to suspend the device by suitable hooks to the framework of 90 the surfacer when desired, though this is not necessary to the successful operation of the device, as it can easily be moved along with the hammer mechanism in passing over the stone.

An apron 17, is conveniently attached to the lower circumference of the device by suitable wire cord extending completely around the base of hood 1, for the purpose of retaining the dust and stone chips within 100 the confines of the hood.

18 is an air inlet or intake hose of the ordinary pneumatic stone surfacing machine, and adapted to operate the hammer mechanism, and conveniently attached by connecting hose to the air reservoir used in the operation of the pneumatic hammer, 19 is the exhaust or discharge from the hammer

mechanism, and like 18 is provided with the ordinary and usual check valves used in such connections.

20 is a pipe with elbows at each end and 5 adapted to adjustment on tube 12 and the exhaust or discharge 19 in the operation of the machinery, thus providing a conduit for the exhaust, discharging the same into the hood 1 through tube 12 and arm 14.

10 21 is the ordinary hammer lever, and 22 the body of the hammer mechanism, which is provided with a supporting framework, 23. The hammer is provided with a handle 24, and all of the ordinary attachments to 10 the pneumatic surfacer as commonly used.

Having described the construction of my device its operation is as follows:—The steel point 4', ordinarily used in connection with granite or stone pneumatic surfacing machines, is first inserted vertically downward 20 through the extension pipe 4, which is telescopically inserted in the tubular neck 2 of the small end 2 of the hood 1; the extension pipe 4 is then adjusted up over the point 4', 25 extending to the base of the hammer mechanism. The elbow arms of pipe 20 are then placed over the exhaust 19 and the tube 12 leading into the hood 1; the hangers 16—16 are then hooked to staples or eyes in the 30 bottom of the hammer framework, and the water tank 10 suitably secured to the lever 21, and the tube 8 is connected therewith by hose 9. Being thus adjusted as to its parts, the air from the main reservoir is turned on 35 at 18, the inlet for the air to the hammer mechanism, and this sets the hammer in motion. The air from the exhaust 19 of the hammer mechanism passes down the pipe 20 and enters hood 1 through the tube 12. 40 At the same time the water is forced through valve 11, permitting the same to flow from tank 10 through hose 9 and into tube 8, and upon passing therefrom into the hood 1, is suddenly and violently struck by the exhaust passing through tube 12, striking it 45 with such force as to convert it into spray, and forcing it through the aperture 5 and into the dust consuming chamber 6. At the same time the exhaust passing out of tube 12, 50 blows and draws the dust made in the operation of the steel point 4', into the dust consuming chamber 6, where it meets and mixes with the spray and is thus converted into solid form, whereupon it drops out of 55 the dust consuming chamber through the opening 7 therein, ready for removal.

The rapidity of the exhaust furnishes a constant supply of air in such quantity as to continually fill the dust consuming chamber with the rising dust and spray when the machine is in operation, and in this way the dust is rapidly and completely transformed into a solid mass, thus obviating the scattering of the same, covering the operators and 65 injuring their eyes, ears, nose and clothing.

Having described my invention what I claim and desire to secure by Letters Patent is:—

1. A dust consuming device of the character described, consisting of a funnel shaped hollow hood, having a tubular neck at the small end and a pipe telescopically adjustable therein; a dust consuming chamber openly connected to the said hood and extending substantially at right angles thereto 70 and having an aperture in the bottom; a tube extending horizontally through the side wall of the said hood and provided with an elbow and arm on the interior thereof; and a tube vertically penetrating the upper wall 80 of the hood and extending downwardly therein, all substantially as set forth.

2. A dust consuming device of the character described, consisting of a funnel shaped hood, having a tubular neck and a pipe telescopically adjustable therein, and provided in its side wall with an opening leading to the dust consuming chamber; a dust consuming chamber connected to said hood and extending substantially at right angles 90 thereto, and having an opening in the bottom extending longitudinally its entire length; a tube extending horizontally through the side wall of the said hood and a pipe adapted thereto; a tube vertically 95 penetrating the upper wall of the hood and a hose and water tank adapted to the said tube; hangers attached to the hood and an apron secured to the large circumference thereof, all substantially as and for the purposes set forth.

3. In a dust consuming device, the combination with a pneumatic surfacing mechanism, provided with an air service pipe leading from the reservoir to the hammer mechanism, of a funnel shaped hollow hood, having a tubular neck and a pipe telescopically adjustable therein and adapted to inclose the surfacing point of the mechanism; a dust consuming chamber attached to the hood having an aperture in the bottom; a tube extending horizontally through the side wall of the hood and adapted to pipe connections with the exhaust of the hammer mechanism; a tube vertically penetrating 110 the upper wall of the hood, adapted to hose connections with the water tank; a water tank connected with said tube and supply and cut off attachments; hangers loosely attaching the hood and dust consuming 115 chamber to the frame-work of the hammer mechanism; and pipe and hose connections, all substantially as set forth.

In testimony whereof I affix my signature in presence of two witnesses.
